UNITED STATES PATENT OFFICE.

JOSEPH E. CLEVELAND, OF COLUMBUS, GEORGIA.

MATTRESS.

Application filed October 1, 1923. Serial No. 665,906.

To all whom it may concern:

Be it known that I, JOSEPH E. CLEVELAND, a citizen of the United States, residing at Columbus, in the county of Muskogee and 5 State of Georgia, have invented certain new and useful Improvements in Mattresses; and I do declare the following to be a full, clear, and exact description of the invention, such as will enable others skilled in the art to 10 which it appertains to make and use the same.

The principal object of my invention is to provide a mattress which is quickly and easily convertible into one of ventilated na- 15 ture, or one of non-ventilated type.

Another aim is to provide a mattress of such construction that movements of a person lying upon the same, will create a circulation of air through the ventilating open- 20 ings, to cool the bed.

With the foregoing in view, the invention resides in the novel subject matter herein- 25 after described and claimed, the description being supplemented by the accompanying drawing.

Figure 1 is a plan view of a mattress constructed in accordance with my invention.

Figure 2 is an enlarged detail sectional view as indicated by line 2—2 of Fig. 1, the 30 plugs for closing the ventilating openings being shown in Figs. 1 and 2.

Figure 3 is a view similar to Fig. 2 but showing the mattress with the plugs re- 35 moved.

Figures 4 and 5 are side elevations looking in different directions at one of the plugs.

Figure 6 is a vertical sectional view on line 6—6 of Fig. 5.

Figure 7 is a horizontal section on line 40 7—7 of Fig. 6.

In the construction of the improved mat- 45 tress, I make use of top and bottom sheets 1 and 2 of ticking or other desired ma- 50 terial, said sheets being stitched or other- 55 wise secured at their edges to an edge wall 3 which may be formed of the same mate- 60 rial. At suitably spaced points throughout their areas, the top and bottom sheets 1 and 2 are formed with vertically alined 65 openings, and ventilating tubes 4 formed of ticking or other suitable flexible material have their ends 5 stitched or otherwise se- 70 cured to the edge walls of said openings, 75 the tubes being of less length than the thick- 80 ness of the mattress stuffing 6, so that sub-

stantially concave form is imparted to the top and bottom of the mattress around each tube end, as indicated by the numerals 7. This formation causes any movements of a 60 person upon the mattress to cause circulation of air through the ventilating tubes 4, thus keeping the bed cool and comfortable in hot weather. I make provision however, whereby the tubes 4 may be closed in cold weather, 65 or if this should otherwise be desirable.

In the present showing, I have provided a plurality of plugs 8 adapted to be frictionally inserted in the sleeves 4 to prevent the passage of air through said sleeves. 70 These plugs are substantially co-extensive in length with the sleeves, and each plug preferably consists of a flexible sack 9 closed about a suitable packing 10 and provided with a strap or other handle 11, by means of which it may be removed when desired. The sacks 9 may well be formed of ticking and the stuffing 10 of raw cotton, which is also preferably used for the stuffing 6. This is not absolutely essential however, as other 75 80 adequate stuffings could be used.

A mattress constructed as, or substantially as shown and described, will be very desirable both in hot and cold weather, may be kept in a fluffy comfortable condition, by compressing it edgewise, both transversely and longitudinally, and will be practically vermin-proof, as no tufts or the like exist in which the vermin may breed and accumulate. Attention may also be directed to the 85 fact that the mattress may be used with either of its sides disposed upwardly and the plugs 8 may be inserted downwardly into the tubes 4, whether the sheet 1 or the sheet 2, be uppermost. Attention may be 90 further invited to the fact that the tubes in question, being of less vertical length than the thickness of the mattress, draw the latter into concave shape at the ends of said tubes, so that both sides of the mattress have 95 a plurality of convex portions, such as those ordinarily produced on mattresses by tufting.

As excellent results may be obtained from the details disclosed, they may be followed 100 if desired, but within the scope of the in- 105 vention as claimed, numerous minor changes may be made.

I claim:

A mattress having a flexible top and bot- 110 tom provided with vertically alined open- 115 ings, a stuffing between said top and bot-

tom, flexible ventilating tubes stitched at their ends to the edges of said openings, said tubes being of less length than the thickness of the packing to impart substantially concave formation to the mattress around the ends of all tubes, and cylindrical plugs insertible into said tubes from either side of the mattress, each plug having a tubular side wall, convex upper and lower end walls, a yieldable packing con-

fined by said walls, and a looped handle secured to the upper end wall, said plugs being of substantially the same length as said tubes and being of a diameter to be frictionally held therein against accidental removal. 15

In testimony whereof I have hereunto affixed my signature.

JOSEPH E. CLEVELAND.
